AIR PROPELLING DEVICE

William Robert Mobley, Miami, Fla., assignor of
one-half to F. W. Bradby, Louisville, Ky.

Application November 12, 1930, Serial No. 495,092

5 Claims. (Cl. 170—168)

The invention or improvements herein described relate to an air propelling device and has for its object to provide a more efficient means of air propulsion than is afforded by propellers according to the present art.

The objects of this invention are accomplished as described in the following specification and drawings in which:

Fig. 1 is a front view.

10 Fig. 2 is a side view having a part removed to more clearly display part of the interior.

Fig. 3 is an enlarged sectional view showing the outer casing in section, together with air stream through the device indicated by arrows.

15 Similar numerals refer to similar parts throughout the several views in which 1 is an outer casing provided with an end plate or the like 2 wherein an opening is arranged as at 3. A part in the form of a suitable hub 4 is located within the outer casing 1. The hub 4 is provided with two or more inclined air propelling blades 7 of such radial extent that they will extend from the hub 4 to the outer casing as at 6 in Fig. 1 at which point they are secured.

20 25 The hub 4 is of suitable diameter and is illustrated as of about the same diameter as the opening 3 and in Figs. 2 and 3 is shown as of half the longitudinal width of the outer casing 1.

The entire device is mounted on an axle, shaft 30 or the like, wherefrom or whereto it may be rotated as a whole. I may house the power plant within the hub 4.

I term the part 4 a hub, it being the central part of the device to which the inner parts of the 35 blades are secured, but it is not ordinarily of solid construction but is shown more like a hollow drum, and this hollow construction would be for the said purpose of housing the power element within the propeller. If the power is to be applied 40 to the said shaft at a point without the propeller in the usual manner it would not be necessary to make the hub hollow but its front plate 4', a part of which is seen in section in Fig. 3, would suffice to prevent the air from passing rearwardly 45 near the shaft and to compel it to pass at and near the periphery of the device within the casing 1. Such plate would also suffice to receive on its rear face the unbalanced atmospheric pressure, which is exerted at points within the blast 50 indicated by the arrows 9 in Fig. 2. This atmospheric pressure is unbalanced because the air is removed from in front of the plate 4' as shown by the arrows 8 (Fig. 3). Said atmospheric pressure at the rear of the propeller gives strong forward 55 propulsion. The diameter of the hub rela-

tive to the casing may be varied to obtain the above mentioned results.

An air screw or helix, according to the present art, revolves in the open air and builds up considerable resistance in front of its center as it advances in a forward direction.

According to the device herein described and with reference being made, particularly to Figs. 1 and 3, it will be observed that the inclined surfaces, vanes or blades 7 are shielded from the open air and that the air stream drawn to the device as it revolves as a whole must enter the opening 3 and be deflected or drawn to the outer periphery of the inside of the device by the blades 7, as indicated by the arrows 8, after which it is forced out of the device, as indicated by arrows 9.

When in rotation the blades 7 of the device will grasp, by their inner edges which extend forward of the hub 4, the body of air which is in front of the hub and within the casing, and will propel said air radially, and thence rearwardly through the annular space between the hub and the casing, and by this action will cause a suction at the opening 3 which will create a vacuum in a small area immediately in front of the device relieving all resistance, thus causing the device to be drawn forward towards the vacuum, while at the same time the discharge of air from the blades 7 creates a pressure forcing the device forward. Due to the shielding of the blades, noise from operation will be greatly decreased. If the casing be omitted the air will not be propelled so directly rearward as shown by the arrows 9 but will be propelled rearward and somewhat radially. I do not confine myself to the angle shown, in the arrangement of the blades, and if the degree of the angle relative to the axial line be increased the blades will be of greater length from their front to their rear edges.

Having now particularly described and ascertained the nature of my invention and the manner in which I propose to perform same, what I claim as new and desire to secure by United States Letters Patent is:

1. A propeller comprising a peripheral casing, a hub arranged at the rear part of said casing so as to leave around it an annular air space and a rear discharge opening and an air-receiving space in front of the hub and within the casing, a front wall extending inward from the casing and having an opening in front of said air-receiving space, and diagonal blades arranged in the annular space between the casing and hub and extending forward around said air-receiving space.

2. A propeller comprising an outer cylindrical casing, a hub member arranged within said casing and at the rear part of the same so as to obstruct the passage of air excepting within and near the inner surface of said casing, said hub having a peripheral wall parallel with the outer casing and extending from the rear of the propeller toward the front thereof, and blades inclined to the axis of the propeller and extending from said hub to said casing and from front to rear of said casing, and a front end plate arranged near the peripheral part of the propeller and leaving an opening in front of said hub for the collection of air.

15. 3. A propeller comprising a hub, blade members attached to said hub at an angle to the axis of rotation, a casing enclosing said hub and blade members, said casing being provided with a front wall having an opening at the center of the front end and an opening around the outer periphery of said hub at the rear end, said blade members extending along the inner face of the casing and along the outer face of said hub.

4. A propeller comprising a peripheral casing, air-obstructing means within the casing for preventing rearward passage of air through said casing excepting at the outer part of the propeller, an annular front wall extending inward from the casing and leaving a large central opening for the entrance of air, and blades arranged between and from front to rear along the casing and said air-obstructing means and inclined to remove air from in front of the propeller.

5. A propeller having an outer casing through which the air may be caused to pass from front to rear of the propeller, a front end plate of annular form extending inward from the front part of said casing and having a front air collecting and entrance opening, a hub arranged within the rear part of said casing and extending forward into the same and leaving an air exit opening between said hub and casing, and blades inclined sidewise and fixed to and arranged along the inner side of the casing and outer side of said hub.

WILLIAM ROBERT MOBLEY.
